DENT-REMOVING TOOL

Laurel M. Back, San Lorenzo, Calif.

Application March 6, 1950, Serial No. 8,361

Term of patent 14 years

(Cl. D54—13)

To all whom it may concern:

Be it known that I, Laurel M. Back, a citizen of the United States and a resident of San Lorenzo, in the county of Alameda and State of California, have invented a new, original, and ornamental Design for a Dent-Removing Tool, of which the following is a specification, reference being had to the accompanying drawings, forming part thereof, wherein,

Figure 1 is a rear perspective view of a dent-removing tool embodying my new design.

Figure 2 is a side perspective view of the tool.

Figure 3 is a full side view of the tool.

I claim:

The ornamental design for a dent-removing tool, substantially as shown.

LAUREL M. BACK.
